US00D905646S

(12) **United States Design Patent** (10) Patent No.: **US D905,646 S**
(45) Date of Patent: **** Dec. 22, 2020**

(54) **SOFTSTARTER**

(71) Applicant: **ABB Schweiz AG**, Baden (CH)

(72) Inventors: **Lars X. Eriksson**, Västerås (SE);
Christopher Lundin, Västerås (SE);
David Wikström, Västerås (SE); **Göran Engblom**, Västerås (SE)

(73) Assignee: **ABB Schweiz AG**, Baden (CH)

(**) Term: **15 Years**

(21) Appl. No.: **29/679,654**

(22) Filed: **Feb. 8, 2019**

(30) **Foreign Application Priority Data**

Aug. 10, 2018 (EM) 005602174

(51) **LOC (12) Cl.** **13-03**

(57) **CLAIM**

The ornamental design for a softstarter, as shown and described.

DESCRIPTION

FIG. 1 is an isometric view of a softstarter in accordance with the new design;

FIG. 2 is a front side elevational view thereof;

FIG. 3 is a rear side elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines in the drawing illustrate portions of the softstarter that form no part of the claimed design.

1 Claim, 7 Drawing Sheets
